2,006,854

DEVICE FOR SETTING AND PROTECTING
DIAMOND-EDGED TOOLS AND THE LIKE

Wilhelm Winter, Hamburg, Germany

Application August 31, 1932, Serial No. 631,291
In Germany September 19, 1931

15 Claims. (Cl. 33—185)

This invention relates to a device for carrying out the vertical and lateral setting and also for the protection of the cutting-edge of hard tools in the case of the employment of a setting-plate 5 situated on the tool-holder at the height of the cutting-edge and in front of the latter.

The invention has as one of its objects the exact vertical and lateral setting of the cutting-edge opposite the work to be operated upon, which for hard tools, for example, diamond tools, is of very special importance, because their output and durability are dependent to a high degree on the very exact observance of the setting.

15. A setting which often deviates from the exactly correct setting only by an amount not perceptible to the naked eye, frequently causes injury to the cutting-edge subjected to strains up to the breaking point, as those skilled in the art understand.

20. In the case of diamond tools the adjustment in height has hitherto been effected by setting a marking-tool, mark-scraper, or drop-point at the height of a certain part of the machine-tool, for example, at the height of the lathe-centre. After this marking-tool has been set, the cutting-edge is brought to the correct height as indicated by said marking-tool by means of packing. When employing this method however 25 the sensitive cutting-edges are very often injured by contact with the marking-tool.

According to the present invention these special conditions for hard tools are accommodated and a device is provided with a setting-plate 30 having its front border or boundary-line corresponding to an enlargement to a very enlarged scale of the cutting edges of the hard cutting body. The device likewise surrounds the hard cutting body and acts as a protection against 35 injury. In cases in which even the enlarged front border or edge is not sufficient for the accurate setting, according to the invention, an extended setting plate is provided by the use of which the setting is easily effected. Such an 40 extension or extended setting plate may be fastened detachably and may be turned or otherwise set according to the angle which the diamond edge is intended to form with the work.

It will be observed that the device is mounted 45 upon the front of a tool preparatory to setting the same with respect to the work in a lathe or the like. Of course, after the tool has been adjusted so that the diamond point is arranged properly in relation to the work, applicant's 50 device is removed from the front of the tool.

The tool can then be brought up to the work and the cutting operation commenced. In other words, applicant's device is mounted upon the tool by means of the large thumb-screw. The tool is then adjusted with respect to the work and the device is then removed so that the tool 5 is free to cut the work.

In order that the setting-plate may be able to follow all possible adjustments of the tool, a special clamping device is provided by the use 10 of which the setting-plate can be fastened directly on the hard tool. The clamping device is provided in special cases with means by the aid of which the distance of the boundary-edge or front of the setting plate from the hard cut- 15 ting-edge can be set.

Now in order to be able to obtain the most accurate agreement of the boundary-edge of the setting plate and the front boundary of the hard tool, a special construction is provided. The device consists of the plate which is preferably transparent and limited substantially by the extended lateral setting edge, which carries a linear and angle scale. The lateral setting edge is directed parallel to the thread of a cross thread 25 of an optical instrument and the optical instrument is so arranged that the cutting edges (facets) of the hard tool can be observed by means of it in a manner well known to those skilled in the art.

In general the movement of the tool with the plate up to the work suffices for accurate setting. Also each edge of the plate may from the start be arranged displaced by such an amount that on bringing a plate-edge parallel to the work the diamond cutting-edge already is set at its correct angle. If consequently, for example, the work is a cylindrical shaft and if the plate-facet be placed suitably against the work the correct setting of the cutting-edge 40 would result.

Several embodiments of the present invention, in which embodiments a diamond turning tool is employed, are illustrated by way of example in the accompanying drawing in which:—

Figs. 1 and 2 are a plan and side elevation respectively of a diamond turning tool;

Figs. 3 and 4 likewise a plan and side elevation respectively of the same diamond turning tool with a setting and protective device mounted thereon;

Fig. 5 is a front elevation of the setting and protective device;

Figs. 6 and 7 are a side elevation and plan of another embodiment of the invention.

Figs. 8 and 9 a side elevation and plan of a further embodiment of the invention;

Fig. 10 shows a construction of the edge extension piece;

5 Fig. 11 shows in side elevation the application of the invention in the case of a hard tool having a circular transverse cross-section;

Fig. 12 a plan corresponding to Fig. 11, and

Fig. 13 a front elevation corresponding to Fig.

10 11.

In the case of the construction according to Figs. 1-5 a diamond *a* is secured on the holder *b* in a well-known manner with the aid of a clamping piece *d*, a fitting plate *c*, situated between said holder *b* and clamping piece *d*, and screw *e*.

20 The setting device consists in the case of the illustrative example, of a cover *f*, which fits accurately over the clamping plate *d* and which can be fixed with the aid of a screw *g*. On the underside of this cover *f* there is fastened by means of screws *h* the setting plate *i*, which consists of sheet steel, celluloid or other suitable material. The front boundary line *k* of the plate *i* is an enlargement to a highly enlarged scale 25 of the cutting edges of the diamond. The plate *i* is provided with a recess *m* into which the diamond projects. In order to protect the diamond edges from injuries from above, a protective plate (see Figs. 8, 9, 11, 12 and 13) is arranged over the recess *m*. In order to be able to set, 30 or to limit, the distance of the front part of the plate *i* from the diamond, there is provided on the cover *f* a screw *n* the point of which abuts 35 against the front of clamping plate *d* and forms a stop.

40 In the case of the embodiment of the invention illustrated in Figs. 6 and 7 a magnifying glass *o* is provided with which the cover *f* is connected and on which the setting-plate *i* is secured with the aid of a holder *r* (or the like). The setting-plate *i* is suitably provided with a scale of the type illustrated and is so set that on viewing coincidence between the diamond 45 and the cross-thread or thread *s* in the magnifying glass, the front edge of the plate *i* gives the correct position of the cutting edge of the diamond. In order to be able exactly to set the small angle possibly necessary between the cutting edge and the work, the plate *i* (Fig. 7) may 50 be provided with a graduated scale *t*.

55 The lateral setting may also as is evident from Fig. 6, be effected by setting or turning the magnifying glass, the angle of deviation being able to be read off on a scale *S*, which is situated above a fixed pointer *j* (Fig. 6) on the magnifying glass *o*.

60 In the case of the construction according to Figs. 8 and 9 there is fitted by means of a screw *u* arranged on the cover *f* and a nut *v* engaging said screw a member *x* provided with a slot *w* for the screw *u*. The edge *y* of member *x* projects downwards as far as is desired and is arranged parallel to the corresponding setting-edge 65 of the plate *i* or if the plate *i* be absent, parallel to or at a definite angle to the diamond cutting-edge. Thus, this edge *y* not only provides protection for the setting plate *i*, but can also be used as a substitute for this setting plate *i*, since it is so constructed that its front edge 70 can be adjusted to be parallel with the front edge of the setting plate *i*. A special slot *z* enables the diamond to be observed from above. With the aid of the member *x* which can be set by being turned and shifted, the exact lateral

setting of the cutting-edge may consequently in this case be effected because the front edge *y* can be set to form any angle with the front edge of the setting plate *i*.

5 In Fig. 10 a modification of the construction of the edge-extension is illustrated. In this case, a piece *i'*, similar to a ruler, is fastened to the plate *i* by means of a screw *i'* in such a manner as to be capable of being rotated and of being displaced horizontally in a slot *i*³ of the plate. 10

In the case illustrated, the long edge *k'* of the piece *i'* is adjusted to be parallel to the front part *k*² of the boundary line of the plate *i* so as to increase its effective length.

15 The embodiment of the invention represented in Figs. 11 to 13 shows the application of the invention in the case of a holder *b*¹ of round cross-section which carries the diamond *a*. In this case the clamping piece is formed as a cylindrical sleeve *f*¹ which can be pushed on the holder *b*¹ and which is fixed in position with the aid of the clamping-screw *g* and which is kept from rotating by means of a pin *g*¹ which engages with its front end in a groove provided in the holder *b*¹. The sleeve *f*¹ is provided above 25 with an observation-hole *m*¹.

20 The setting plate *i* is fixed on the sleeve *f*¹ with the aid of screws *i*⁵, and a protective plate *l* of mica or other transparent material is connected thereto. The plate *l* covers the diamond 30 and protects it from injury, to which it might be liable on account of the existence of the observation-hole *m*¹.

What I claim is:—

35 1. A device for the exact vertical and lateral setting of the cutting-edge of hard-tools in relation to the work and for the protection thereof which comprises a clamping device capable of being detachably mounted on a tool-holder containing a cutting diamond, a setting-member associated with said clamping device, said setting-member having a front boundary-line situated at the same height as the cutting edge of the diamond and having enlarged faces parallel to the front facets of the cutting diamond 40 whereby the cutting-edge is prevented from coming in contact with the work during the setting of the cutting-edge.

45 2. A device for the exact vertical and lateral setting of the cutting-edge of hard-tools in relation to the work and for the protection thereof which comprises a clamping device capable of being detachably mounted on a tool-holder containing a cutting diamond, a setting-member associated with said clamping device 50 and surrounding said cutting diamond, said setting-member having a front boundary-line situated at the same height as the cutting-edge of the diamond and having enlarged faces parallel to the front facets of the cutting diamond, 55 whereby the cutting-edge is prevented from coming in contact with the work during the setting of the cutting-edge.

60 3. A device for the exact vertical and lateral setting of the cutting-edge of hard-tools in relation to the work and for the protection thereof which comprises a clamping device capable of being detachably mounted on a tool-holder containing a cutting diamond, a plate associated 65 with said clamping device, said plate having a front boundary-line situated at the same height as the cutting-edge of the diamond and having enlarged faces parallel to the front facets of the cutting diamond whereby the cutting-edge is 70 75

prevented from coming in contact with the work during the setting of the cutting-edge.

4. A device for the exact vertical and lateral setting of the cutting-edge of hard-tools in relation to the work and for the protection thereof which comprises a clamping device capable of being detachably mounted on a tool-holder containing a cutting diamond, a setting-member associated with said clamping device, said setting-member having a front boundary-line situated at the same height as the cutting edge of the diamond and having enlarged faces parallel to the front facets of the cutting diamond, said clamping device and plate surrounding the cutting edge of said diamond whereby the cutting-edge is prevented from coming in contact with the work during the setting of the cutting-edge.

5. A device for the exact vertical and lateral setting of the cutting-edge of hard-tools in relation to the work and for the protection thereof which comprises a clamping device capable of being detachably mounted on a tool-holder containing a cutting diamond, a plate associated with said clamping device, having a front boundary-line situated at the same height as the cutting-edge of the diamond and having enlarged faces parallel to the front facets of the cutting diamond, said plate being provided with an extension piece capable of being fastened at any predetermined angle with relation to the enlarged faces so as to increase their effective length, whereby the cutting edge is prevented from coming in contact with the work during the setting of the cutting-edge.

6. A device for the exact vertical and lateral setting of the cutting-edge of hard-tools in relation to the work and for the protection thereof which comprises a clamping device capable of being detachably mounted on a tool-holder containing a cutting diamond, a plate associated with said clamping device having a front boundary-line situated at the same height as the cutting-edge of the diamond and having enlarged faces parallel to the front facets of the cutting diamond, said plate being provided with a displaceable and revolute extension piece capable of being fastened at any predetermined angle with relation to the enlarged faces so as to increase their effective length whereby the cutting edge is prevented from coming in contact with the work during the setting of the cutting-edge.

7. A device for the exact vertical and lateral setting of the cutting-edge of hard-tools in relation to the work and for the protection thereof which comprises a clamping device capable of being detachably mounted on a tool-holder containing a cutting diamond, a setting-member associated with said clamping device, said setting-member having a front boundary-line situated at the same height as the cutting-edge of the diamond and having enlarged faces parallel to the front facets of the cutting diamond and a displaceable and revolute separate boundary-edge extension member capable of being mounted on the tool-holder by means of the said setting member.

8. A device for the exact vertical and lateral setting of the cutting-edge of hard-tools in relation to the work and for the protection thereof which comprises a clamping device capable of being detachably mounted on a tool-holder containing a cutting diamond, a setting-member associated with said clamping device, said set-

ting-member having a front boundary-line situated at the same height as the cutting-edge of the diamond and having enlarged faces parallel to the front facets of the cutting diamond and a displaceable and revolute separate boundary-edge extension member mounted on the clamping device, capable of being fastened at any predetermined angle with relation to the enlarged faces so as to increase their effective length whereby the cutting-edge is prevented from coming in contact with the work during the setting of the cutting-edge.

9. A device for the exact vertical and lateral setting of the cutting-edge of hard-tools in relation to the work and for the protection thereof which comprises a clamping device capable of being detachably mounted on a tool-holder containing a cutting diamond, said clamping device being in the form of a cover provided with a protective plate, a setting-member associated with said clamping device, said setting member having a front boundary-line situated at the same height as the cutting-edge of the diamond and having enlarged faces parallel to the front facets of the cutting diamond whereby the cutting-edge is prevented from coming in contact with the work during the setting of the cutting-edge.

10. A device for the exact vertical and lateral setting of the cutting-edge of hard-tools in relation to the work and for the protection thereof comprising a clamping device capable of being detachably mounted on a tool-holder containing a cutting element, said clamping device being in the form of a cover provided with a protective plate and said cover having a clamping screw and a screw distance-adjustment stop, a setting-member associated with said clamping device, said setting-member having a front boundary-line situated at the same height as the cutting element and having faces parallel to the facets of the cutting element whereby the cutting-edge is prevented from coming in contact with the work during the setting of the cutting-edge.

11. A device for the exact vertical and lateral setting of the cutting-edge of hard-tools in relation to the work and for the protection thereof which comprises a clamping device capable of being detachably mounted on a tool-holder containing a cutting element, a transparent setting-member associated with said clamping device, said setting-member having a front boundary-line situated at the same height as the cutting element and having at least one face parallel to one facet of the cutting element whereby the cutting-edge is prevented from coming in contact with the work during the setting of the cutting-edge.

12. A device for the exact vertical and lateral setting of the cutting-edge of hard-tools in relation to the work and for the protection thereof which comprises a clamping device capable of being detachably mounted on a tool-holder containing a cutting diamond, a setting-member associated with said clamping device, said setting-member having a front boundary-line situated at the same height as the cutting-edge of the diamond and having at least one enlarged face parallel to the front facets of the cutting diamond and an optical magnifying instrument mounted on said clamping device, having cross threads in fixed relation to the setting member adapted to be adjusted so as to coincide with the cutting-edge of the diamond whereby the cutting-edge is prevented from coming in contact

with the work during the setting of the cutting-edge.

13. A device for the exact vertical and lateral setting of the cutting-edge of hard-tools in relation to the work and for the protection thereof which comprises a clamping device capable of being detachably mounted on a tool-holder containing a cutting diamond, a setting-member having a scale and being mounted on said clamping device, said setting-member having front boundary-lines situated at the same height as the cutting-edge and having at least one enlarged face parallel to the front facets of the cutting diamond, and an optical magnifying instrument mounted on said clamping device, having cross threads in fixed relation to the setting member adapted to be adjusted so as to coincide with the cutting-edge of the diamond whereby the cutting-edge is prevented from coming in contact with the work during the setting of the cutting-edge.
14. A device for the exact vertical and lateral setting of the cutting-edge of hard-tools in relation to the work and for the protection thereof which comprises a clamping device in the form of a displaceable non-revolvable sleeve capable of being detachably mounted on a tool-holder con-
15. A device for the exact vertical and lateral setting of the cutting-edge of hard-tools in relation to the work and for the protection thereof which comprises a clamping device capable of being detachably mounted on a tool-holder containing a cutting diamond, a setting-member pivotably mounted on said clamping device, said setting-member having a front edge situated at the same height as and in front of the cutting-edge of the diamond, an optical instrument associated with said setting-member, said optical instrument having cross threads in fixed relation to the front edge of said setting member and adapted to coincide with the cutting-edge of the diamond whereby the front edge of said setting-member may be set at any predetermined angle with relation to the said cutting-edge.

5

taining a cutting diamond, a setting-member associated with said clamping device, said setting-member having a front boundary-line situated at the same height as the cutting-edge of the diamond and having enlarged faces parallel to the front facets of the cutting diamond whereby the cutting-edge is prevented from coming in contact with the work during the setting of the cutting-edge.
